UNITED STATES PATENT OFFICE.

JOHN WALDHEIM, OF ELIZABETH, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,374,969.

Specification of Letters Patent. Patented Apr. 19, 1921.

Application filed November 27, 1918. Serial No. 264,300.

To all whom it may concern:

Be it known that I, JOHN WALDHEIM, a citizen of the United States, residing in Elizabeth, in the county of Union and State 5 of New Jersey, have invented certain new and useful Improvements in Combined Typewriting and Computing Machines, of which the following is a specification.

This invention relates generally to combined typewriting and computing machines, and more particularly to the class in which two computing units are used, namely, a column-computing unit and a cross-computing unit; each unit comprising two elements, namely, a totalizer and a master wheel, one of said elements being adapted to travel relatively to the other through a computing zone.

In such machines there is usually provided 20 an automatic pick-up mechanism to cause the traveling element of the cross-computing unit to travel step by step with the corresponding element of the column-computing unit through a computing zone; the 25 pick-up mechanism being engaged by adjustable devices on the typewriter carriage. These pick-up devices may be in the form of tabulator-stops, adapted to engage with a suitable pick-up hook to actuate the latter 30 when the carriage passes through a computing zone, said movement being transmitted through suitable mechanism to the cross-totalizer.

It is sometimes desirable to disconnect or 35 silence the computing mechanism. For this purpose, there is usually provided a silencing element actuated by a "non-compute" key.

An object of this invention is to render 40 the pick-up mechanism ineffective when the computing mechanism is disconnected, thus avoiding unnecessary movements of the cross-totalizer and consequently reducing the wear and tear of the machine.

To do this, there is preferably provided 45 a train of mechanism extending from the non-compute key to engage the pick-up hook, to remove the latter out of effective relation with the pick-up elements when the 50 computing mechanism is silenced by the non-compute key.

In carrying out the invention, it is shown as applied to an Underwood Addendagraph of the type disclosed in the application of 55 Henry L. Pitman, Serial No. 186,098, filed

August 14, 1917, in which both column and cross-totalizers are employed, each being provided with computing wheels which are caused to traverse a relatively fixed master wheel. 60

Other features and advantages will hereinafter appear.

In the accompanying drawings,

Figure 1 is a part sectional side view of an Underwood Addendagraph machine, 65 showing the invention applied thereto.

Fig. 2 is a fragmentary rear view of the machine, showing the carriage passing through a computing zone, with the cross-totalizer. 70

Fig. 3 is a rear view, showing the pick-up hook rendered ineffective.

Fig. 4 is a skeleton, perspective view of the invention, viewed from the front, and upper right-hand corner of the machine. 75

Numeral keys 10 and alphabet keys 11, when actuated, move key-levers 12 about their fulcrums 13, to swing bell-cranks 14 which engage with type-bars 15 to swing the latter upwardly and rearwardly about 80 a fulcrum 16, and cause types 17 to print against the front side of a rotatable platen 18. The platen is supported on a carriage 21 which is adapted to move, under the influence of a spring drum 22, connected 85 thereto by a suitable strap 23, and moves on a front rail 24 and a rear rail 25 from the right to the left of the machine during letter-feeding movements. These letter-feeding movements of the carriage are controlled by a dog-rocker 26 comprising a loose dog 27 and a fixed dog 28; said dog-rocker being actuated by a cross-bar 31 of a frame 32, having at its forward end a curved universal bar 33 which is engaged 90 by heels 34 on the type-bars 15, to move said frame 32 rearwardly as the type approaches the printing point. The loose and fixed dogs vibrate back and forth during letter-feeding operations between teeth 35 of the 100 escapement wheel 36 which has the usual one-way connection with a pinion 37 meshing with a rack 38 supported on the carriage.

To compute the numbers as they are 105 typed, the key-levers of the numeral keys 10 are provided with cam plates 41 having slots 42 therein which vary in shape to rock a bail 43 through different angular distances according to the values of the nu- 110

2

meral keys; said bail forming part of a differential rocking frame 44 comprising also an intermediate member 45 which pulls downwardly on a link 46 to transfer said movements, by means of a train of mechanism, as disclosed in said Pitman application, to a master wheel 47 contained within an actuator 48 of the column-computing unit 51. The movements of the master wheel are transferred to dial wheels 52 by means of intermediate pinions 53 contained within a totalizer 54 of the column-computing unit; said totalizer being adjustably supported on a truck 55 which is adapted to travel on a fixed rail 56 and with the typewriter carriage 21, so as to bring the intermediate pinions 53 of said totalizer 54 into effective relation with said master wheel 47 *seriatim*; connections between said truck 55 and said carriage 21 being made by one or more arms 59 extending from said carriage.

A cross-computing unit 57, comprising an actuator 58 and a cross-totalizer 61, is also provided and located at the lower right-hand side of the machine; said actuator 58 comprising a master wheel 62 which is adapted to be driven in unison with the master wheel 47 of the column-computing unit. To do this, a shaft 63, which forms part of the train of mechanism between the connecting link 46 and the master wheel 47 of the column-computing unit, has thereon a beveled gear 64 meshing with a beveled gear 65 secured to the upper end of a vertical shaft 66 extending downwardly to the actuator 58 of the cross-computing unit 57; connections from said shaft 66 to the master wheel 62 of the cross-computing unit being made in a similar manner as that disclosed in the Pitman application herein referred to.

The totalizer 61 of the cross-computing unit is also mounted on a truck 67 adapted to run on a fixed guide rail 68, and is adapted to traverse the master wheel 62 every time a column-totalizer passes through a computing zone.

To cause this movement of the cross-totalizer 61, there may be provided on the typewriter carriage adjustable devices engaging with suitable pick-up mechanism connected with the cross-totalizer, which serves to cause the cross-totalizer to travel with the typewriter carriage. These adjustable devices may be in the form of column-stops 71 adjustably mounted on a stop bar 70 secured to the typewriter carriage.

The pick-up mechanism may include a pick-up bar 72, Fig. 2, having a hook 73 thereon with which the column-stops 71 engage. Said pick-up bar normally occupies a position toward the right-hand side of the machine, where a pin 74 on said pick-up bar bears against the end 75 of a slot 76 formed 65 in a fixed cam plate 77. It is also held

against the upper edge 78 of the cam plate 77 by a spring 81 through the intermediary of a lever 82 having a stud 83 which bears against the under side of said pick-up bar 72. When, however, a column-totalizer 70 passes through a computing zone, the corresponding column-stop 71 engages with the pick-up bar 72 to move it rightwardly in Fig. 2 to swing a substantially vertically disposed lever 84 about its pivot 85, the lower end of said lever having a slot 86 to receive a rearwardly extending arm 87 of an intermediate member 88 pivotally supported at 91 on a fixed bracket 92; said intermediate member having a forwardly projecting arm 93 suitably connected with the truck 67 on which said cross-totalizer 61 is supported. A suitable return spring 94 is connected between the lever 84 and a pin 95 on said fixed bracket 92.

After the typewriter carriage has passed through a computing zone, the pick-up bar 72 becomes disconnected from the column-stop by a cam 96 on the fixed cam plate 77, said cam being engaged by the pin 74 on said pick-up bar. The hook 73 on said pick-up bar is thus moved out of engagement with the column-stop 71, whereupon the pick-up mechanism and the cross-totalizer are restored to their normal positions by the return spring 94.

It is sometimes desired to disconnect the computing mechanism, so that numbers may be typed without transferring their values to the totalizers. To do this, there is provided a silencing device 97 which may be actuated by a non-compute key 98 through the intermediary of a link 101 which may be moved rearwardly when the non-compute key is set to a silencing position. When said silencing device 97 is actuated, it swings an interponent 102 about its pivot 103 to break the connection between the bail 43 and the intermediate element 45, which is normally maintained by a spring 104 which holds said interponent against a pin 105 on said bail 43 in such a way as to form a rigid connection between said bail and said intermediate element. The intermediate element 45 is, however, loosely mounted on a rock shaft 106 which comprises part of said bail 43 and forms a fulcrum therefor. It will be seen that when the interponent 102 is moved out of effective relation with the pin 105 on said bail that said bail will be actuated idly when moved by the cams 41 on the numeral keys. In other words, the movements imparted to said bail 43 are not at this time transferred to the master wheels.

This invention comprises means to render the pick-up bar ineffective, and preferably at a time when the computing machine is silenced. This may be done by a train of mechanism connected to the non-compute key 98 and may comprise a link 107 which is

5 moved forwardly when the non-compute key is moved to its silencing position; said link being effective to rock a shaft 108 by means of an upwardly extending arm 111 connected to said link, said rock shaft being supported in a suitable bracket 112 secured to the machine frame, and having a forwardly projecting arm 113 thereon which is adapted to pull downwardly on a bar 114 guided in 10 a suitable bracket 115 and having at its upper end a hook or finger 116 which overlies said pick-up bar, so as to swing the latter about its point of connection 117 on the lever 84, Fig. 2, and thus move the 15 hook 73 on said pick-up bar 72 out of effective relation with the column stops 71, as shown in Fig. 3, so that the typewriter carriage 21 may travel back and forth without effecting a picking up of the cross-totalizer 20 61. Due to the fact that the pick-up bar lies close to the lower edges of the column-stops 71, Figs. 1 and 2, the pick-up bar is cut out at 118 to permit the hook 116 to overlie said pick-up bar and still clear the 25 lower edges of said column-stops 71.

Any convenient form of detent may be provided to maintain the non-compute key 98 in the positions to which it may be moved.

The column-stops 71 are used, in the well-known manner, in combination with denomination-stops or plungers 119, which may be actuated to release the carriage and position it in any denomination of the several columns.

35 Variations may be resorted to within the scope of the invention, and portions of the improvements may be used without others.

Having thus described my invention, I claim:

40 1. In a combined typewriting and computing machine, the combination of a typewriter carriage, a cross-totalizer, pick-up devices on said carriage, an intermediate member spring-pressed upwardly to enable engagement thereof by said pick-up devices, means whereby said intermediate member when in engagement with one of said pick-up devices will cause the cross-totalizer to be advanced with the carriage, a lever pivoted on the typewriter frame near the front thereof, and means actuated by said lever, including a member having a hook overlying said intermediate member, to withdraw said intermediate member from the path of said 55 pick-up devices.

2. In combination, typewriting mechanism, including a typewriter carriage, alphabet and numeral keys for actuating said typewriting mechanism, a movable finger-piece mounted adjacent said keys, a cross-totalizer, means to feed said cross-totalizer with said carriage, including pick-up dogs mounted on said carriage at its rear and a member spring-pressed into position to be 60 engaged by said dogs and advanced there-

with, and means actuated by said finger-piece to withdraw said spring-pressed member from the path of said dogs.

3. In a combined typewriting and computing machine, the combination of a carriage, pick-up dogs on said carriage, a cross-totalizer, means to feed said cross-totalizer with said carriage, including a member yieldably positioned to be engaged by said dogs and advanced therewith, a link having 70 at one end a hook engaging said member, to enable the withdrawal of the latter from the path of said dogs, a bell-crank having one of its arms pivoted to the other end of said link, and means for actuating said bell-crank, including a finger-piece mounted on the machine near the front thereof.

4. In a combined typewriting and computing machine, the combination of a carriage, pick-up dogs on said carriage, a cross-totalizer, means to feed said cross-totalizer with said carriage, including a member yieldably positioned to be engaged by said dogs and advanced therewith, a link having 80 at one end a hook engaging said member, 90 to enable the withdrawal of the latter from the path of said dogs, a bell-crank having one of its arms pivoted to the other end of said link, a finger-piece near the front of the machine, and a link connecting said finger-piece to the other arm of said bell-crank.

5. In a combined typewriting and computing machine, the combination with a carriage, a cross-totalizer, pick-up means for said cross-totalizer, and computing mechanism for actuating said cross-totalizer, of means to silence the computing mechanism, and means controlled by said silencing means to render said pick-up means ineffective.

6. In a combined typewriting and computing machine, the combination with a carriage, a cross-totalizer, and computing mechanism for actuating said cross-totalizer, of means to cause said cross-totalizer 110 to travel with said carriage when the latter enters a computing zone, silencing means for the computing mechanism, and means to render said first-mentioned means ineffective when said silencing means is actuated.

7. In a combined typewriting and computing machine, the combination of a carriage and a cross-totalizer, computing mechanism, pick-up means to cause said cross-totalizer to travel with said carriage when the latter enters a computing zone, silencing means for the computing mechanism, a non-compute key to actuate said 120 silencing means, and means connected to 125 said key to render said pick-up means ineffective.

8. In a combined typewriting and computing machine, the combination of a typewriter carriage, a cross-totalizer, pick-up 130

dogs on said carriage, means to feed said cross-totalizer with said carriage, including a member yieldably positioned in the path of said dogs to be engaged thereby and advanced therewith, and means, including a finger-piece at the front of the machine, for withdrawing said member from the path of said dogs.

9. In a combined typewriting and computing machine, the combination with a carriage, of a cross-totalizer, computing means for actuating said cross-totalizer, silencing means for said computing means, including a finger-piece, dogs on said carriage, a member yieldably supported in the path of said dogs to be engaged thereby and advanced therewith, connections between said cross-totalizer and said member, to enable actuation of the former by the latter, and means actuated by said finger-piece for withdrawing said member from the path of said dogs.

10. In a combined typewriting and computing machine, the combination of a carriage, a totalizer, denomination-selecting means, including a reciprocable pick-up element associated with said totalizer, adjustable devices on said carriage to engage said pick-up element and actuate the same, a link having a hooked end engaging said element, a finger-piece mounted in the front part of the machine, and means whereby actuation of said finger-piece will actuate said link and thereby withdraw said element from the path of said adjustable devices.

11. In a combined typewriting and computing machine, in combination, a carriage, a column-totalizer traveling therewith, com-

puting mechanism for actuating said column-totalizer, a cross-totalizer, computing mechanism for actuating said cross-totalizer, said cross-totalizer-actuating mechanism being actuated by said column-totalizer-computing mechanism, pick-up means for said cross-totalizer, means to silence said column-totalizer-computing mechanism, and means, controlled by said silencing means, for rendering said pick-up means ineffective.

12. In a combined typewriting and computing machine, in combination, a carriage, a column-totalizer to travel therewith, computing mechanism for said column-totalizer, a cross-totalizer, pick-up mechanism to cause said cross-totalizer to travel with said carriage, means to silence said computing mechanism, and means, controlled by said silencing means, to render said pick-up mechanism ineffective.

13. In a combined typewriting and computing machine, in combination, a carriage, a column-totalizer traveling therewith, computing mechanism for said totalizer, a cross-totalizer, computing mechanism for said cross-totalizer, pick-up mechanism to connect said cross-totalizer with said carriage, to feed it past its computing mechanism, means to silence the column-totalizer-computing mechanism, and means, controlled by said silencing means, for concomitantly silencing said cross-totalizer computing mechanism and said pick-up mechanism.

JOHN WALDHEIM.
